UNITED STATES PATENT OFFICE.

HEREWARD S. SCOTT, OF DETROIT, MICHIGAN.

NEWSPAPER FILE.

Application filed February 20, 1925. Serial No. 10,542.

In Patent No. 866,391, dated Sept. 17, 1907, there is disclosed a file that may be advantageously used as a temporary binder or filing device for newspapers and similar sheets, the filing device including impaling pins on which newspapers or like sheets may be impaled and retained thereon by a closure member placed on the pins. A simple and durable structure supports the pins and closure member, and provision is made for holding the closure either in an open position or in a closed position relative to the impaling pins.

This invention aims to provide a somewhat similar filing structure including certain improvements or refinements which afford a better device. One of the improvements are resilient end members which serve two purposes, first, that of holding a closure in a closed position, and second, that of aligning the upper and lower edges of sheets in the filing structure and protecting upper and lower corners of said sheets, without interfering with turning of the sheets for inspection purposes.

My invention further aims to provide a filing device in which sheets of paper cannot become accidentally dislodged when the closure of the device is in an open position, as edges of the sheets of paper are positioned under ledges that will prevent impaled sheets of paper from being forced off of the impaling pins of the device. It is a well known fact that when crowding a binder or filing device that the uppermost sheets must be very often placed under compression until the binder is closed. In my device the uppermost sheets of paper will be positively held in position so that the closure member of the device can be closed and all of the sheets of paper firmly held.

My invention still further aims to provide a binder or filing device of large capacity that may be advantageously used for weekly filings of newspapers in newspaper offices, libraries and other institutions, and the device includes a closure with positive and reliable means for retaining the closure in a closed position, so that the expansive force of stacked or compressed papers cannot force the closure open.

My invention will be hereinafter specifically described and then claimed, and refer-

ence will now be had to the drawing, wherein—

Figure 1 is a perspective view of the filing device or binder;

Fig. 2 is a rear elevation of the same partly broken away;

Fig. 3 is a cross sectional view of the filing device taken on the line III—III of Fig. 2, showing the closure of the device in an open position;

Fig. 4 is a similar view showing the closure of the device in a closed position;

Fig. 5 is a detail view of one of the resilient end members or ledges of the device, and

Fig. 6 illustrates a slight modification in connection with the lower tube or back member.

To put my invention into practice, I select two metallic tubes 1 and 2 of equal length and in the tube 2, at suitable intervals, are anchored the lower ends 3 of impaling pins 4, said pins having the upper ends thereof pointed so that sheets of paper or other filing material 5 may be easily placed down over the pins.

Attached to the lower tubular member by rivets or other fastening means are the lower barrel ends 6 of back members 7 which are disposed in parallelism with the plane of the pins 4 and the upper ends of said back members are enlarged to provide apertured ears 8 and ledges 9, said ledges being parallel to the lower end portions 10 of the back members in order that the paper sheets 5 may be placed in stacked formation between the lower end portions 10 of the back members 7 and the ledges 9 thereof, with the uppermost paper sheet engaging under the ledges 9. This is particularly true when the filing device or binder approaches a full condition, as brought out in Fig. 4, and it is obvious that the ledges 9 will cooperate with the impaling pins 4 in preventing dislodgment of the paper sheets.

Pivotedly mounted between the apertured ears 8 of the back pieces 7, by pins 11, rivets or the like, are the small barrel ends 12 of hinge members 13 which have large barrel ends 14 embracing the upper tubular member 1 and cooperating therewith in providing a closure. The large barrel ends 14 are riveted or otherwise connected, as at 15

to the tube 1 and said tube is apertured, as at 16 to receive the pointed ends of the impaling pins 4. With the closure swingable to and from the pins 4 it may be easily opened or closed and to hold it closed resilient end members 17 are employed.

In the ends of the tube 2 are placed plugs 18 which may be retained therein by rivets 19 or other fastening means and the lower ends of the resilient end members 17 are riveted or otherwise attached to the plugs, as at 20. The upper ends of the resilient end members 17 are provided with outward turned lips or finger pieces 21 and with beveled lugs or latches 22 which are adapted to engage in the open ends of the tube 1 and hold the closure in a closed position. The lugs or latches 22 are of a configuration to fit within the ends of the tube 1 and are beveled in order that the closure may be lowered and snapped into engagement with the resilient end members 17. The finger pieces 21 of these end members permit of the same being shifted outwardly, as suggested by dash lines in Fig. 5, when it is desired to open the closure. The lugs or latches 22 may be spot welded, riveted or otherwise attached to the end members 17, as at 23. The end members not only serve as resilient detents in connection with the closure but afford end binders which will cooperate with the impaling pins 4 in properly stacking paper sheets and it will be noted by reference to Fig. 1 that the upper and lower edges of the paper sheets will be somewhat protected adjacent the binder or filing device.

Comparing the present invention with that disclosed in the prior patent, above referred to, it will be noted that the lower end portions 10 of the present back members 7 will cooperate with the tubular bottom member 2 in providing a substantial support for papers, in contradistinction to the lower tubular member in the patent. Again, the upper tubular member shown in the patent was held in a closed position by flat springs associated with the hinge and it was found that a weekly issue of newspapers crowded the filing device to such an extent that the upper tubular member was forced open against the action of the flat springs, there being no positive latching device as in my present invention. The lugs or latches 22 present shoulders against which the upper tubular member engages without stressing the end members 17 to such an extent that said members snap open. In other words, the stress and strain exerted by newspapers in my present file is in a direction at right angles to that which would open the end members 17, and it is only necessary to have these mem-

bers of sufficient resiliency to retain the lugs or latches in the ends of the upper 65 member.

As shown in Fig. 6, a back member 7 may have its lower end disposed at an obtuse angle and formed with a barrel for embracing the lower tube 2. In this construction the back member extends under the tube and may be considered a reverse arrangement of that shown in Figs. 3 and 4.

One embodiment of my invention has been illustrated, but it is to be understood that the structural elements are susceptible of such variations and modifications as fall within the scope of the appended claims.

What I claim is:—

1. A filing device comprising a lower member, an upper member, back members hingedly supporting said upper member from the lower member, paper retaining means carried by said lower member, and engageable by said upper member and disposed in a plane constantly parallel to said back members, said back members having ledges in proximity to said paper retaining means to retain paper in engagement with said means when said upper member is disengaged from said paper retaining means, and means carried by said lower member and engaging the ends of said upper member to retain it in a closed position relative to said lower member.

2. A filing device including paper impaling pins, a hinged closure to engage the upper ends of said pins and retain paper on said pins, and supporting means for said hinged closure adapted to retain paper on said pins independent of said hinged closure.

3. A newspaper filing device comprising a lower member, back members carried thereby, said back members having lower horizontal end portions and upper ledge portions adapted for engagement with newspapers, paper impaling pins on said lower member with the ends of said pins spaced from the upper ledge portions of said back members, an upper member hingedly supported by said back members and adapted to engage said pins, and end members on said lower member spaced from said back members to engage the ends of said upper member to hold it closed relative to said pins.

4. A newspaper filing device as called for in claim 3, wherein said upper and lower members are hollow and said end members are resilient and fixed to the ends of said lower member and adapted to be sprung relative to the ends of the upper member.

In testimony whereof I affix my signature.

HEREWARD S. SCOTT.
